[57] CLAIM

The ornamental design for a soap bar, substantially as shown and described.

DESCRIPTION

FIG. 1 is a perspective view of a soap bar showing my new design;

FIG. 2 is a top plan view thereof with the bottom plan view being substantially identical thereto;

FIG. 3 is a sectional view taken along the lines 3—3 in FIG. 2;

FIG. 4 is a top plan view of a soap bar showing a modified form of my new design, the bottom being substantially identical thereto; and

FIG. 5 is a sectional view taken along the lines 5—5 in FIG. 4.

FIG. 1

FIG. 2

FIG. 3

FIG. 4

FIG. 5
